B. HOE AND CO., OF NEW YORK, N. Y., A CORPORATION OF NEW YORK.

CASTING-BOX.

1,117,980.

Specification of Letters Patent. Patented Nov. 24, 1914.

Application filed January 8, 1904. Serial No. 137,865.

To all whom it may concern:

Be it known that I, AMANDUS H. CRUSE, a citizen of the United States, residing at New York, county of Kings, and State of New York, have invented certain new and useful Improvements in Casting-Boxes, fully described and represented in the following specification and the accompanying drawings, forming a part of the same.

10 This invention relates to certain improvements in casting boxes such as are used in printing offices for casting stereotype plates.

In casting boxes as ordinarily constructed, the box is trunnioned on a pair of supports and the cover is hinged to the body. In the operation of such boxes, the cover is first thrown down onto the body so as to close the box and then the body and cover are swung together into a vertical position to enable the metal to be poured. These boxes require in operation considerable physical exertion and they are, therefore, slow and tiring to the operators.

25 It has been proposed to employ boxes in which one part of the box is fixed or stationary in an upright position, the other part being moved toward and away from the stationary part and then swung from a horizontal to a vertical position, and vice versa, in order to close the box and open it to remove the cast plate from the mold. Inasmuch as the stationary back is usually provided with grooves so as to cast ribs onto the plate, it is desirable that when the box is opened to remove the plate, the movable part at the beginning of the opening movement travels away from the stationary part in substantially a straight line so as 30 to pull the ribs on the plate straight away from the grooves. In one form of this box, namely, that shown in the patent to Brooks, No. 351,040, dated Oct. 19, 1886, the body is trunnioned on a carriage, the cover being maintained in a substantially upright position, and after the box has been poured the carriage is moved back in a straight line until the body is clear of the cover, after 35 which the body is swung into a horizontal position so that the casting may be removed therefrom. This form of box is advantageous because in opening the box, the movable body travels in a right line away from the stationary part, and because only that 40 part of the box which carries the plate has

to be moved. This box is, however, objectionable because it is slow in operation; owing to the fact that the movement which must be given the carriage in order to close the box is very considerable, and, furthermore, the movable part is not balanced, so that considerable force is required to shift it from its vertical to its horizontal position. The box is also complicated in construction and therefore expensive.

35 One of the objects of this invention is to produce an improved casting box which shall have one of its parts maintained in a substantially upright position, the other part being caused to slide toward and away 40 from the vertically arranged part and at the same time to turn from a horizontal to a vertical position.

45 A further object of this invention is to produce an improved casting box having one of its parts maintained in a substantially vertical position, the other part being arranged to slide toward and away from the vertically arranged part and at the same time to tilt from a substantially horizontal 50 to a substantially vertical position, or vice versa, the guides and supports by which the movable part is controlled being so arranged that the box is balanced in any of its 55 positions.

60 A further object of this invention is to produce an improved casting box having one of its parts maintained in a substantially vertical position, the other part being arranged to slide toward and away from the vertically arranged part and at the same 65 time to tilt from a substantially horizontal to a substantially vertical position, or vice versa, the guides and supports by which the movable part is controlled being so arranged 70 that the box is balanced in any of its positions, locking devices being also provided, the movable part being brought into the range of action of these devices by the movement before referred to, and said devices serving to close, open and hold the 75 body in locked relation with the vertically arranged part.

80 With these and other objects in view, the invention consists in certain constructions, 85 and in certain parts, improvements and combinations as will be hereinafter fully described and then specifically pointed out in the claims hereunto appended.

85 Referring to the accompanying draw- 90

ings—Figure 1 illustrates in side elevation a form of box embodying the invention, the box being shown in its open position. Fig. 2 is a view similar to Fig. 1, but showing the box in its closed position. Fig. 3 is a front view of the box.

Referring to the drawings which illustrate one concrete embodiment of the invention, 1 indicates a base to which one of the parts of the box, in the present instance, the cover, marked 2, is secured in a substantially vertical position. This cover is shown as provided with the usual grooves 3 by which the ribs cast on the backs of stereotype plates are produced. The body portion of the box, which is marked 4, is disconnected from the cover portion and is arranged to slide toward and away from the cover and at the same time to turn or tilt from the horizontal position illustrated in Fig. 1 to the vertical position illustrated in Fig. 2.

The means by which the sliding and turning movements referred to are effected may be widely varied. As shown, a guide is provided on which this movable part of the box moves. This guide may be widely varied in form and construction. As shown, it consists of a pair of side frames or plates 5, these frames or plates being shown as bolted to the base 1. In the construction shown which illustrates a preferred form, these side frames are formed to provide a pair of curved tracks 6 which are formed on the top of the frames and are substantially horizontal, that is to say, they extend in a generally horizontal direction. The side frames are also formed to provide a pair of tracks 7 which are inclined to the vertical and are preferably somewhat curved, the outline being substantially that illustrated.

The body portion of the box is caused to move on these tracks and to swing from its horizontal open position to a vertical position. The devices by which the body is supported on the guide before described may be widely varied and will vary according to the particular form and construction which may be given the guide. As shown, the body portion is provided with two pairs of studs 8, 9, the studs 8 being preferably located, as shown, above the vertical center of the body portion and the other pair of studs being located near the bottom of the body portion. To render the box easy of operation these studs preferably carry suitable anti-friction rolls, the rolls on the studs 8 being marked 10 and the rolls on the studs 9 being marked 11. The box will preferably be provided with suitable handles as shown, said handles being marked 12.

In the preferred form of the construction, the guide will be so constructed and the rolls so located that the body portion will be in perfect balance for any intermediate position between the vertical and the horizontal positions.

By this construction, the labor of operating the box is reduced to a minimum and a box is produced which is very easy and rapid in operation.

In the box shown, which is of the usual form for casting curved plates, the body portion, after being brought into substantially vertical position, is given a limited straight line movement to bring it into operative relation with the cover. The object of this movement is, after a plate has been cast, to move the body portion away from the substantially vertical cover, so as to pull the ribs of the plate out of the grooves of the cover. This straight line movement may be effected by any suitable means, but it will preferably be effected by the same devices which operate to lock the body portion in its closed position with respect to the cover portion.

In the construction shown which illustrates the preferred form, two shafts 13 and 14 are provided, the shaft 13 being mounted in suitable bearings 15 secured to the cover, and the shaft 14 being mounted in suitable bearings 16 also secured to the cover. The shaft 13 carries a pair of locking members 17, these members being provided with grooved cam slots 18 said slots coöperating with pins 19 secured to the body at any suitable point. As shown, these pins 19 are held on the body portion of the box by clips 20, and the pins are located at about the center of the body. The box is also provided with a set of pins 21 located as shown at the bottom of the body portion these pins coöperating with locking members 22. These members consist of sliding plates which are provided with slots 23, and in the construction illustrated they are connected by pins 24 to short crank arms 25 on the shaft 14. Preferably, and as shown, the two sets of locking members will be simultaneously operated. While this may be effected in any desired manner, as shown the shaft 13 is provided with a slotted crank arm 26 and the shaft 14 is provided with a slotted crank-arm 27, these arms being connected by a suitable link 28. The shaft 13 is provided with a suitable operating handle 29. In the operation of the box, as it moves from its horizontal to its vertical position, the pins 21 enter the slots 23 in the sliding members 22 and the pins 19 are positioned so as to be engaged by the slots 18 in the members 17. The shafts are operated through the connections described by turning the handle 29, this operation causing the body to be given a right line movement toward the upright cover, the parts being so arranged that as this right line movement is completed the body portion is locked to the cover. After the metal is poured in the usual way, the shafts 13 and 14 are given

a reverse movement. The slotted members operating against the pins force the body portion carrying the cast plate in a right line away from the cover portion, after 5 which the operator or operators seize the handles 12 and slide the body back on the guide, the body turning as it moves back into the horizontal position illustrated in Fig. 1.

10 The body is or may be provided with the usual curved head gage 30 and the usual retaining devices 31 for the bars 32 which hold the matrix in place.

It is customary in operating boxes of this 15 character to throw the cast plate forward by swinging the head gage, and in doing this there is a tendency, when the box is horizontal, to depress the end of the box at which the head gage is located. To prevent 20 this, in the preferred construction, suitable locking devices will be provided, although these devices, under some circumstances may be omitted, if desired. In the construction shown, these devices consist of hooks 34 25 which are pivoted at 35 to the side frames, these hooks being provided with handles 36 by which they are operated.

It will be understood that either the cover or the body of the box may be movable 30 with relation to the other part, but in the preferred construction and as shown, the body will be made the movable part. It will be further seen that by balancing the movable part and causing it to turn as it 35 slides on the guide, the operators do not have to lift this movable part at all, and the action of the box is consequently very easy and rapid.

While the construction illustrated is the 40 preferred one, it is to be understood that the invention may be embodied in constructions which differ widely therefrom. The invention is not, therefore, to be limited to the particular construction herein described 45 and illustrated.

What is claimed is:—

1. In a casting box, the combination with a part maintained in a substantially vertical 50 position, of a movable part disconnected therefrom, and means for supporting and guiding said movable part so that it may be given a simultaneous sliding and swinging movement whereby it is caused to approach the vertical part and to turn from a substantially horizontal to a substantially vertical position, substantially as described.

2. In a casting box, the combination with a part maintained in a substantially vertical 55 position, of a movable part disconnected therefrom, and means arranged above the bottom of the movable part for supporting and guiding it so that it may be given a simultaneous sliding and swinging movement, whereby it is caused to approach the 60 vertical part and turn from a substantially

horizontal to a substantially vertical position.

3. In a casting box, the combination with a part maintained in a substantially vertical position, of a movable part disconnected 70 therefrom, and means for supporting and guiding said movable part so that it may be given a simultaneous sliding and swinging movement whereby it is caused to approach the upright part and to turn from a substantially horizontal to a substantially vertical position, said means being constructed and arranged so that the movable part is balanced in any position thereof, substantially as described. 80

4. In a casting box, the combination with a part maintained in a substantially vertical position, of a movable part disconnected therefrom, and means arranged above the bottom of the movable part for supporting 85 and guiding said movable part so that it may be given a simultaneous sliding and swinging movement whereby it is caused to approach the upright part and to turn from a substantially horizontal to a substantially vertical position, said means being constructed and arranged so that the movable part is balanced in any position thereof. 90

5. In a casting box, the combination with a part maintained in a substantially vertical 95 position, of a movable part disconnected therefrom, means for supporting and guiding said movable part so that it may be given a simultaneous sliding and swinging movement whereby it is caused to approach the upright part and to turn from a substantially horizontal to a substantially vertical position, and devices for closing, opening 100 and locking the part in its closed position, the movable part being brought within the range of action of said devices by the sliding and swinging movement, substantially as described.

6. In a casting box, the combination with a part maintained in a substantially vertical 110 position, of a movable part disconnected therefrom, means for supporting and guiding said movable part so that it may be given a simultaneous sliding and swinging movement whereby it is caused to approach the vertical part and to turn from a substantially horizontal to a substantially vertical position, said means being constructed 115 and arranged so that the movable part is balanced for any position thereof, and devices for closing, opening and locking the part in its closed position, the movable part being brought within the range of action of said devices by the sliding and swinging movement, substantially as described. 120

7. In a casting box, the combination with a part maintained in a substantially vertical position, of a movable part having suitable supporting devices, said devices including anti-friction rolls, and a guide with which 125 130

- 5 said rolls coöperate, the movable part moving from a substantially horizontal to a substantially vertical position, the guide and supporting devices being constructed and arranged so that the movable part is balanced for any position thereof, substantially as described.
- 10 8. In a casting box, the combination with a part maintained in a substantially vertical position, of a movable part having supporting devices including anti-friction rollers, a guide comprising tracks with which said rollers coöperate, the movable part moving from a substantially horizontal to a substantially vertical position, the supporting devices and guide being constructed and arranged so that the movable part is balanced for any position thereof, substantially as described.
- 15 9. In a casting box, the combination with a part maintained in a substantially vertical position, of a movable part having two sets of supporting devices thereon, and a guide comprising two sets of tracks with which said devices coöperate, the movable part moving from a substantially horizontal to a substantially vertical position, the supporting devices and guide being constructed and arranged so that the movable part is balanced for every position thereof, substantially as described.
- 20 10. In a casting box, the combination with a part maintained in a substantially vertical position, of a movable part having two sets of supporting devices, each set including suitable anti-friction rollers, a guide comprising two pairs of tracks with which said devices coöperate, the movable part moving from a substantially horizontal to a substantially vertical position, the supporting devices and guide being constructed and arranged so that the movable part is balanced for every position thereof, substantially as described.
- 25 11. In a casting box, the combination with a part maintained in a substantially vertical position, of a movable part having suitable supporting devices, a guide with which said devices coöperate, the movable part moving from a substantially horizontal to a substantially vertical position, the guide and supporting devices being constructed and arranged so that the movable part is balanced for every position thereof, and suitable devices for closing and opening the box and for locking it in its closed position, substantially as described.
- 30 12. In a casting box, the combination with a part maintained in a substantially vertical position, of a movable part having two sets of supporting devices, each set including suitable anti-friction rollers, a guide comprising two pairs of tracks with which said devices coöperate, the movable part moving from a substantially horizontal to a substantially vertical position, the supporting devices and guide being constructed and arranged so that the movable part is balanced for every position thereof, and suitable devices for closing and opening the box and for locking it in its closed position, substantially as described.
- 35 13. In a casting box, the combination with a part maintained in a substantially vertical position, of a movable part having supporting devices, a guide comprising tracks with which said supporting devices coöperate, the movable part moving from a substantially horizontal to a substantially vertical position, the supporting devices and guide being constructed and arranged so that the movable part is balanced for any position thereof, and suitable devices for closing and opening the box and for locking it in its closed position, substantially as described.
- 40 14. In a casting box, the combination with a part maintained in a substantially vertical position, of a movable part having supporting devices including anti-friction rollers, a guide comprising tracks with which said rollers coöperate, the movable part moving from a substantially horizontal to a substantially vertical position, the supporting devices and guide being constructed and arranged so that the movable part is balanced for any position thereof, and suitable devices for closing and opening the box and for locking it in its closed position, substantially as described.
- 45 15. In a casting box, the combination with a part maintained in a substantially vertical position, of a movable part having two sets of supporting devices thereon, a guide comprising two sets of tracks with which said devices coöperate, the movable part moving from a substantially horizontal to a substantially vertical position, the supporting devices and guide being constructed and arranged so that the movable part is balanced for every position thereof, and suitable devices for closing and opening the box and for locking it in its closed position, substantially as described.
- 50 16. In a casting box, the combination with a part maintained in a substantially vertical position, of a movable part having two sets of supporting devices, each set including suitable anti-friction rollers, a guide comprising two pairs of tracks with which said devices coöperate, the movable part moving from a substantially horizontal to a substantially vertical position, the supporting devices and guide being constructed and arranged so that the movable part is balanced for every position thereof, and suitable devices for closing and opening the box and for locking it in its closed position, substantially as described.
- 55 17. In a casting box, the combination with a part maintained in a substantially vertical position, of a movable part having suitable supporting devices, said devices including anti-friction rolls, a guide with which said

17. In a casting box, the combination with a cover maintained in a substantially vertical position, of a movable body having supporting devices including anti-friction rollers thereon, a guide with which said rollers coöperate, the body moving from a substantially vertical to a substantially horizontal position, the guide and supporting devices being constructed and arranged so that the body is balanced in any position with respect to the guide, and suitable devices for closing, opening and locking the box, substantially as described.
18. In a casting box, the combination with a cover maintained in a substantially vertical position, of a movable body, said body having two sets of supporting devices thereon, one set being arranged above the vertical center of the body and the other being arranged near the bottom thereof, and a guide with which said supporting devices coöperate, the supporting devices and guide being constructed and arranged so that the movable body is balanced for every position thereof, substantially as described.
19. In a casting box, the combination with a cover maintained in a substantially vertical position, of a movable body, said body having two sets of supporting devices thereon, one set being arranged above the vertical center of the body and the other being arranged near the bottom thereof, a guide with which said rollers coöperate, the supporting devices and guide being constructed and arranged so that the movable body is balanced for every position thereof, and suitable devices for closing and opening the box and for locking it in its closed position, substantially as described.
20. In a casting box, the combination with a cover maintained in a substantially vertical position, of a movable body portion, said body portion having two sets of supporting devices comprising anti-friction rolls, and a guide comprising two sets of tracks with which said rolls coöperate, the supporting devices and guide being constructed and arranged so that the movable body portion is balanced in any position with respect to the guide, substantially as described.
21. In a casting box, the combination with a cover maintained in a substantially vertical position, of a movable body portion, said body portion having two sets of supporting devices comprising anti-friction rolls, a guide comprising two sets of tracks with which said rolls coöperate, the supporting devices and guide being constructed and arranged so that the movable body is balanced for every position thereof, and suitable devices for closing and opening the box and for locking it in its closed position, substantially as described.
22. In a casting box, the combination with a cover maintained in a substantially vertical position, of a body portion having two sets of supporting devices each set comprising anti-friction rolls, one set being arranged above the vertical center of the box and the other near its bottom, and a guide comprising a pair of horizontally arranged curved tracks and a pair of inclined tracks, the upper set of rolls coöperating with the horizontal tracks and the lower set of rolls with the inclined tracks, the supporting devices and guide being constructed and arranged so that the movable body is balanced in any position with respect to the guide, substantially as described.
23. In a casting box, the combination with a cover maintained in a substantially vertical position, of a body having two sets of supporting devices each set comprising anti-friction rolls, one set being arranged above the vertical center of the box and the other near its bottom, a guide comprising a pair of horizontally arranged curved tracks and a pair of inclined tracks, the upper set of rolls coöperating with the horizontal tracks and the lower sets of rolls with the inclined tracks, the supporting devices and guide being constructed and arranged so that the movable body is balanced in any position with respect to the guide, and suitable devices for closing and opening the box and for locking it in its closed position, substantially as described.
24. In a casting box, the combination with a part maintained in a substantially vertical position, of a movable part having suitable supporting devices, a guide with which said devices coöperate, the movable part moving from a substantially vertical to a substantially horizontal position, and the guide and supporting devices being constructed and arranged so that the movable part is balanced for any position thereof, and two sets of mechanisms for opening and closing the box and for locking it in its closed position, one of said sets coöperating with the upper part and the other with the lower part of the box, substantially as described.
25. In a casting box, the combination with a part maintained in a substantially vertical position, of a movable part having suitable supporting devices, a guide with which said devices coöperate, the movable part moving from a substantially vertical to a substantially horizontal position, and the guide and supporting devices being constructed and arranged so that the movable part is balanced for any position thereof, two sets of mechanisms for opening and closing the box and for locking it in its closed position, one of said sets coöperating with the upper part and the other set with the lower part of the box, and means for operating said mechanisms simultaneously, substantially as described.

26. In a casting box, the combination with a part maintained in a substantially vertical position, of a movable part having suitable supporting means, a guide with which said means coöperate and along which the movable part is arranged to slide and upon which it turns from a substantially vertical to a substantially horizontal position, mechanism operating on the bottom of the part, and mechanism operating above the bottom of the part, said mechanisms being brought into operation after the movable part has reached its vertical position for moving it toward the vertical part, and for moving it away from said part after pouring, substantially as described. 70
27. In a casting box, the combination with a part maintained in a substantially vertical position, of a movable part having suitable supporting devices, a guide with which said devices coöperate and along which the movable part is arranged to slide and upon which it turns from a substantially vertical to a substantially horizontal position, the guide and supporting devices being constructed and arranged so that the movable part is balanced for every position of the part, and means brought into operation after the movable part has reached its vertical position for moving it away from the fixed part after pouring, substantially as described. 75
28. In a casting box, the combination with a part maintained in a substantially vertical position, of a movable part having suitable supporting means, a guide with which said means coöperate and along which the movable part is arranged to slide and upon which it turns from a substantially vertical to a substantially horizontal position, mechanism operating on the bottom of the movable part, and mechanism operating above the bottom of the part, said mechanisms being brought into operation after the movable part has reached a substantially vertical position and serving to close, lock and open the box, substantially as described. 80
29. In a casting box, the combination with a part maintained in a substantially vertical position, of a movable part having suitable supporting devices, a guide with which said devices coöperate and along which the movable part is arranged to slide and upon which it turns from a substantially vertical to a substantially horizontal position, the guide and supporting devices being constructed and arranged so that the movable part is balanced for every position of the part, mechanism operating on the bottom of the movable part, and mechanism operating above the bottom of the part, said mechanisms being brought into operation after the movable part has reached a substantially vertical position and serving to close, lock and open the box, substantially as described. 85
30. In a casting box, the combination with a cover maintained in a substantially vertical position, of a guide having tracks, a body portion arranged to slide on the tracks and to be guided thereby as it moves from a substantially horizontal to a substantially vertical position, pairs of slotted members coöperating with the body, and means for operating the members to open, close and lock the body in coöperative relation with the cover, substantially as described. 90
31. In a casting box, the combination with a cover maintained in a substantially vertical position, of a guide having two sets of tracks, a body portion having two sets of rolls coöperating with the tracks, the tracks and rolls being so arranged that the body is balanced in any position with respect to the cover, a pair of suitably mounted shafts, a pair of slotted members on each shaft, connections between the shafts, and means for operating one of the shafts, substantially as described. 95
32. In a casting box, the combination with a cover maintained in a substantially vertical position, of a guide comprising two sets of tracks, a body portion arranged to slide on the tracks from a horizontal to a vertical position, and means for locking the body portion in its horizontal position, substantially as described. 100
33. In a casting box, the combination with a cover maintained in a substantially vertical position, of a guide having tracks, a body portion arranged to slide on the tracks and to be guided thereby as it moves from a substantially horizontal to a substantially vertical position, pairs of slotted members coöperating with the body, and means for operating the members to open, close and lock the body in coöperative relation with the cover, substantially as described. 105
34. In a casting box, the combination with a cover maintained in a substantially vertical position, of a guide having two sets of tracks, a body portion having two sets of rolls coöperating with the tracks, the tracks and rolls being so arranged that the body is balanced in any position with respect to the cover, a pair of suitably mounted shafts, a pair of slotted members on each shaft, connections between the shafts, and means for operating one of the shafts, substantially as described. 110
35. In a casting box, the combination with a cover maintained in a substantially vertical position, of a guide having tracks, a body portion arranged to slide on the tracks and to be guided thereby as it moves from a substantially horizontal to a substantially vertical position, pairs of slotted members coöperating with the body, and means for operating the members to open, close and lock the body in coöperative relation with the cover, substantially as described. 115
36. In a casting box, the combination with a cover maintained in a substantially vertical position, of a guide having two sets of tracks, a body portion having two sets of rolls coöperating with the tracks, the tracks and rolls being so arranged that the body is balanced in any position with respect to the cover, a pair of suitably mounted shafts, a pair of slotted members on each shaft, connections between the shafts, and means for operating one of the shafts, substantially as described. 120
37. In a casting box, the combination with a cover maintained in a substantially vertical position, of a guide having tracks, a body portion arranged to slide on the tracks and to be guided thereby as it moves from a substantially horizontal to a substantially vertical position, pairs of slotted members coöperating with the body, and means for operating the members to open, close and lock the body in coöperative relation with the cover, substantially as described. 125
38. In a casting box, the combination with a cover maintained in a substantially vertical position, of a guide having two sets of tracks, a body portion having two sets of rolls coöperating with the tracks, the tracks and rolls being so arranged that the body is balanced in any position with respect to the cover, a pair of suitably mounted shafts, a pair of slotted members on each shaft, connections between the shafts, and means for operating one of the shafts, substantially as described. 130

tical position, of a guide comprising two sets of tracks, a body portion arranged to slide on the tracks from a horizontal to a vertical position, means for locking the body portion in its horizontal position, and devices for opening, closing and locking the body portion to the vertical cover, substantially as described.

36. In a casting box, the combination with 10 a cover maintained in a substantially vertical position, of a guide comprising two pairs of tracks, a body portion mounted to slide and turn on said tracks from a substantially horizontal to a substantially vertical

position, means for locking the body in a 15 horizontal position, a pair of suitably mounted shafts; a pair of slotted locking members on each shaft, connections between the shafts, and means for operating one of the shafts, substantially as described.

20 In testimony whereof, I have hereunto set my hand, in the presence of two subscribing witnesses.
